UNITED STATES PATENT OFFICE.

BENJAMIN F. HAUGE, OF ANDERSON, INDIANA.

CAR-COUPING KNUCKLE.

1,078,498.

Specification of Letters Patent. Patented Nov. 11, 1913.

Original applications filed August 11, 1910, Serial Nos. 576,711 and 576,712. Divided and this application filed March 14, 1912. Serial No. 683,825.

To all whom it may concern:

Be it known that I, BENJAMIN F. HAUGE, a citizen of the United States, residing at Anderson, Madison county, and State of Indiana, have invented and discovered certain new and useful Improvements in Car-Coupling Knuckles, of which the following is a specification.

The object of my said invention is to provide a knuckle for car couplers, the wearing points of which will be re-inforced by hardened metal capable of prolonging the life of the knuckle by affording to said wearing parts greater resistance to the wear than can be afforded by the metal of which the body of the knuckle is composed.

It also consists in providing a knuckle having said supplemental wearing parts cast integrally with the body of the knuckle and wearing surfaces thus provided of a smooth and true contour and accurately located in the knuckle to secure the best results.

The processes by which said knuckle is formed are more fully described in my applications #576,711 and #576,712, filed August 11, 1910, and of which the present application is a division.

Referring to the accompanying drawings which are made a part hereof and on which similar reference characters indicate similar parts: Figure 1 is a perspective view of the car coupling knuckle constructed in accordance with my said invention, Fig. 2, a detailed section on the dotted line 2—2 in Fig. 1, Fig. 3 a detailed section on the dotted line 3—3 in Fig. 1, and Fig. 4 a cross section on the dotted line 4—4 in Fig. 1.

In said drawings the main body of the knuckle is designated by the reference letter A and is of a standard or any approved form and composed of cast metal, such as is usually used for the purpose. The hole for the coupling pin in said knuckle is provided with a tubular lining 10 which is preferably cast therein in the manner described in my above mentioned application #576,711. Said lining consists preferably of metal having the characteristic of hardening during the process of cooling after the casting operation has been completed. The ends of said tube extend to points just within the outer limits of the pin hole so that the cast metal overhangs the ends thereof and thus secures it against the possibility of any loosening or accidental removal.

The insert plates 11 are embedded in the wearing face of the "ear" of the knuckle, the center of the plates being located on the draft line. The edges of said plates are also completely surrounded by the cast metal so that they are substantially embedded in the casting. Their edges are preferably tapered so that the metal of the casting overhangs said edges somewhat and secures a dove-tailed connection. In their ends are formed centrally located notches in which anchor pins *a* engage, said anchor pins being partly in the cast metal and partly in said notches and located on the draft line. By this means the said plates are centrally secured on the draft line and being formed of the proper contour are held in position where no change or irregularity in the proper contour of the wearing face will be made. Said interlocking pins and notches serve to hold said plates securely against lateral displacement even after the overhanging portion of the casting is worn away.

In the construction of the knuckle it is important to secure uniformity in the wearing life between the several portions thereof. To this end the plates 11 and pin hole line 10 coöperate and prolong the ordinary life of the knuckle uniformly. While either of said improvements will serve to prolong the life of its particular part of the knuckle, one without the other will not be as efficient inasmuch as the life of the knuckle is only as long as the life of any one of its parts. When the pin hole is worn to the point where it must be re-placed the life of the knuckle is gone, even though the wearing face of the "ear" may yet be in efficient condition, and the reverse of the statement is equally true. The best results and greatest advantages are therefore attained in a knuckle comprising all of the improvements set forth.

The use of such a knuckle will not only result in economy in equipment by saving a large part of the expense for the knuckles on account of their much longer life but also in greater safety, inasmuch as many accidents are caused by the breaking of knuckles at one or the other of these points or because of their inefficient service resulting from wear in one point or the other or both, causing a looseness between the parts which permits the parts to separate and the train to divide.

Having thus fully described my said invention, what I claim as new and desire to secure by Letters Patent, is—

1. As an article of manufacture, a knuckle 5 for car-couplers formed with its pin hole lined with a tube of self-hardening metal secured therein during the process of casting with its ends overhung by said casting, and with the wearing face of its "ear" armed on 10 the draft line with wearing plates also composed of self-hardening metal secured in place during the process of casting and with their edges completely surrounded and embedded in the cast metal and interlocked 15 therewith, substantially as set forth.

2. As an article of manufacture, a car-coupling knuckle formed of cast metal with

hardened metal plates inserted in the face of its "ear" on the draft line and secured therein during the process of casting by embedding said plates in the cast metal, and having a pin hole also lined with a tube of hardened metal formed therein during the process of casting and embedded in the cast metal, substantially as set forth.
